UNITED STATES PATENT OFFICE.

HUBERT J. ECHELE AND EUGENE E. KERN, OF ST. LOUIS, MISSOURI; SAID KERN AS-SIGNOR TO WILLIAM R. ALBERTS, OF ST. LOUIS, MISSOURI.

DISPLAY DEVICE.

Application filed March 21, 1928. Serial No. 263,238.

This invention relates to illuminated signs and is illustrated herein as embodied in a lamp provided with a translucent globe, and an illuminating unit adapted to project upon the translucent globe, printed matter or other indicia carried by a screen interposed between the illuminating unit and the globe.

An object of the invention consists in providing an improved light of this character in which the screen interposed between the illuminating unit and the lamp globe rotates constantly, and the image projected upon the globe is distorted during the rotation of the screen in such a manner as to produce a most unusual yet harmonious effect. A feature of the invention which leads to the accomplishment of this object consists in forming the lamp globe of a plurality of flat panels so assembled that the globe is polygonal in cross sectional shape whereby the focus of an image projected from the illuminating unit (which is located in the center of the globe) changes as the image passes from the center of one of the flat panels of the globe to a more remote portion of the panel located adjacent an apex of the polygonal figure. As this change in the focus takes place, the size of the image increases, and then as the image passes from the remote portion of the next panel back to the center of the next panel, the size of the image decreases.

Another feature of the invention consists in applying reading matter or other design to the rotary screen and in projecting this reading matter upon the globe in a manner in which it may be most easily read and sharply defined.

Still another feature consists in providing a novel means for use in rotating the screen, which means, as illustrated, comprises an induction disc motor acting continuously on a plate carried by the screen. The motor is also provided with means which may be regulated to govern and control the speed and the direction of rotation of the screen.

Other features and objects of the invention will become apparent from a reading of the specification in the light of the accompanying drawings, in which:

Fig. 1 is a view in front elevation of one of the invented lamps in operation,

Fig. 2 is a vertical section taken along the line 2—2 of Fig. 1,

Fig. 3, is a horizontal section taken along the line 3—3 of Fig. 2, and,

Fig. 4, is a diagrammatical view illustrating the manner in which the lamp functions.

The reference numeral 10 indicates a hollow base arranged to conceal an electric cord 12, and provided with an annular shoulder 14 for receiving the lower extremity of the lamp globe. This globe comprises, generally speaking, a lid 16, a joining ring 18, a plurality of glass panels 20, a base joining ring 22 and a plurality of side wall braces, or supports 24 arranged to hold the glass panels in their proper positions within the globe.

For the purpose of illuminating the lamp the electric cord 12 leads to a socket 26 which is supported by means of a bracket 28 and in turn supports a bulb or other illuminating unit 30.

As hereinbefore pointed out the glass panels of the globe are translucent and there is provided means for projecting a plurality of images upon the panels of the glass. The means for projecting these images comprises a rotary screen 32 composed of some suitable material, as for example, parchment or celluloid, upon which decorative designs of various sorts may be applied. To the end of rotating the screen a plate 34 comprising the head of said screen composed of aluminum or other suitable material is provided at its central portion with a glass cup 36 for engagement by the needle point of a support 38, whereby the frictional engagement between the support and the screen is materially reduced. An induction coil or motor 40 depends from a strap 42 and upon being energized, serves to rotate the disk located there beneath. It is observed that an adjustable support 46 permits the induction coil to be raised or lowered to vary the speed of rotation of the screen in accordance with the proximity of the coil.

As will be observed from an inspection of Figs. 1 and 2, printed matter is applied to the screen in approximately the same horizontal plane with the filament of the bulb or illumination unit 30 whereby the image projected by the bulb will be impinged upon the glass panels in a clear and

sharply defined manner. In this connection it is to be observed that the construction of the lamp globe tends itself greatly to produce a harmonious and pleasing effect as the printed matter is displayed on the exterior of the globe. Thus, the flat panels provide back-grounds for receiving the traveling images of the letters; the braces 24 tend to break the monotony of a constant stream of letters or words; and the provision of a plurality of panels arranged in the manner illustrated permits the printed matter to be read from all sides of the lamp, while enabling one standing directly in front of one of the panels to view the next adjacent panels so that he may read the letters ahead of those appearing on the panel before which he stands as well as those appearing upon the panel behind the one before which he stands.

Turning now to a consideration of Figs. 1 and 4, it is desired to point out that by virtue of the construction herein illustrated and described the images projected upon the glass panels of the globe are periodically distorted in a way that presents a pleasing appearance. For example, looking at Fig. 4 an examination of the manner in which a decoration *a* appears from time to time as it is projected upon the translucent panels reveals that the image *b* is comparatively large when the decoration is projected upon the portion of the panel farthest removed from the source of illumination, and as the image moves near the center of the panel, and approaches somewhat the filament of the bulb, it not only becomes smaller and more distinct and sharp, but also it moves upwardly towards the center of the panel, and then downwardly after having passed the center of the panel.

By virtue of the lamp operating in the above described manner, a screen speckled in appearance and bearing thereon the word "Fizz" will present an appearance approximating that illustrated in Fig. 1, wherein the projected images bulge upwardly at the bottom of each panel, and downwardly at the top of each panel. During the rotation of the screen this tendency on the part of the projected images presents a wavy appearance to one viewing the lamp, which is more pleasing in appearance when it is remembered that the size of each image at the top and bottom of the panels is constantly changing. The use of colors in decorating the screen enhances the attractiveness of the lamp and is contemplated by the present invention.

Having thus described the invention what we claim as new and desire to secure by Letters Patent of the United States is:

1. An illuminated display comprising, in combination, a housing having translucent wall portions, a source of illumination lo-

cated within said housing, a rotary screen surrounding the source of illumination, and an induction disk motor for imparting movement to said screen, said induction disk motor including a plate, a pivot by which said plate is supported for rotary movement, and an induction coil for influencing said plate to cause same to rotate on said pivot, said screen being fixed to said plate in a manner to balance said plate on its pivot. 75

2. An illuminated display comprising, in combination, a housing having translucent wall portions, a source of illumination located within said housing, a rotary screen surrounding the source of illumination, and an induction disk motor for imparting movement to said screen, said induction disk motor including a plate, a pivot by which said plate is supported for rotary movement, and an induction coil for influencing said plate to cause same to rotate on said pivot, said screen being fixed to said plate and being arranged in depending relation with respect thereto and to said pivot so as to balance said plate during movement thereof on said pivot. 85

3. An illuminated display comprising, in combination, a housing having translucent wall portions, a source of illumination located within said housing, a rotary screen 95 surrounding the source of illumination, and an induction disk motor for imparting movement to said screen, said induction disk motor including a plate, a pivot on which said plate rotatably rests and an induction coil for influencing said plate to cause same to rotate on said pivot, said screen being fixed to said plate and being arranged in depending relation with respect thereto and to said pivot so as to balance said plate during movement thereof on said pivot. 100

4. An illuminated display device comprising, in combination, a housing having translucent wall portions, a source of illumination located within said housing, a rotary 110 screen surrounding the source of illumination, an induction disk motor for imparting movement to said screen, said induction disk motor including a plate, a pivot by which said plate is supported for rotary 115 movement, and an induction coil for influencing said plate to cause same to rotate on said pivot, said screen being fixed to said plate in a manner to balance said plate on its pivot, and means providing for the adjustment of said induction coil with respect to said plate. 120

5. In a display apparatus, the combination of a source of illumination, a rotary light emitting display screen surrounding the source of illumination, and an induction disk motor including a plate forming a fulcrum head for the screen, said motor being next to and acting directly upon the screen for imparting rotary motion thereto. 125 130

6. An illuminated display, comprising, in combination, a housing having translucent wall portions, a source of illumination located within said housing, a rotary screen surrounding the source of illumination, and an induction disk motor acting directly upon said screen for imparting motion thereto, said induction disk motor including a plate forming the fulcrum head of said
- screen and directly carried thereby, and an induction coil for influencing said plate, whereby rotary movement is imparted thereto.
- 5 In testimony that we claim the foregoing we hereunto affix our signatures.
